UNITED STATES PATENT OFFICE

2,286,345

PAUSE CONTROL SYSTEM FOR DICTATION
REPRODUCING MACHINESHenry P. Clausen, White Plains, N. Y., assignor
to The Gray Manufacturing Company, Hartford, Conn., a corporation of Connecticut

Application January 3, 1941, Serial No. 372,972

9 Claims. (Cl. 274—9)

This invention is specifically concerned with improvements in machines for reproducing for the purposes of transcription, dictated matter recorded on record tablets.

An object of the invention is the provision of a control-system for such transcription machines in the form of a separate unit which may be readily associated with various forms of transcription machines, that is, machines for reproducing, for purposes of transcription, sound records by means of which the rate of sound reproduction may be simply predetermined and then automatically attained.

The more detailed objects of the invention will become apparent from the following detailed description of the single embodiment thereof diagrammatically illustrated in the attached drawing and described below in detail for the purpose of disclosing the nature and scope of the invention.

This invention resides substantially in the combination, construction, arrangement, and relative location of parts, all as will be explained in full detail hereinafter.

In the accompanying drawing, the single figure is a diagrammatic illustration of an assemblage of elements embodying the novel functions and features of this invention.

In the every day use of sound reproducing machines for reproducing recorded dictation for the purposes of transcription, it is desirable, if not necessary, to provide mechanism which will permit the transcribing operator to start and stop the machine as the rate of reproduced dictation requires, in order to permit the operator to keep up her transcription with the rate of reproduction.

In the simplest arrangements of the prior art systems, the transcriber is provided with a start and stop control device for stopping the machine at intervals and again starting it. Obviously such an arrangement takes the operator's mind from her work and interferes with the recording of the transcribed matter, whether it be stenographic or typed. For this reason such systems are obviously far from convenient and efficient.

Systems have been devised where after the transcribing machine has been started it will stop automatically after reproducing a given unit of words, but in such systems it is necessary for the operator to again start the machine after having transcribed the reproduced matter. This is obviously inconvenient and time consuming. Other systems have been incorporated directly in the machine as a part thereof, by means of

which the machine automatically starts and stops so as to reproduce a given unit of words and then to stop for a given period of time, after which it again automatically goes into operation. Such a system is inflexible in that it is not adapted to the varied abilities of the transcribers which may use it, so that it may slow up their work. Another disadvantage is that such arrangements are incorporated in as a part of the transcribing machine, and hence are not available for use with other machines.

Speaking in general in accordance with this invention, the pause control mechanism is a separate unit which may be used with a number of machines and adapted to use therewith. In addition it is so constructed that the rate of reproduction may be varied to suit the varied capabilities of the different transcribing operators who may use it, and as to particular transcribers it is adapted to easy variation in the rate of sound reproduction to accommodate it to the nature and complexity of the subject matter being transcribed. The mechanism of this invention need only be interconnected with the starting and stopping control circuits of the machine to convert that machine to an automatically operating mechanism variable as to the rate of reproduction.

The transcribing machine diagrammatically illustrated herein is similar in type to that disclosed in the co-pending application of Barton A. Proctor and Ferdinand C. W. Thiede, Serial No. 218,082, filed July 8, 1938. As illustrated in the drawing, the machine includes a rotatable spindle 1, having a notched or suitably shaped end 2 on which the record tablet 3 is impaled so as to be keyed thereto for rotation with it. The record tablet may be of any suitable form but is preferably in the form of a disc of thin cellulose acetate, smooth on both sides, and having a central opening complementarily shaped to the end 2 of the shaft 1 so as to fit snugly thereon.

The spindle 1 is journaled in a carriage 4 which is mounted for sliding movement on a pair of rods or rails (not shown) so that it may be moved back and forth. Secured to the shaft 1 is a worm gear or wheel 5 which meshes with a threaded shaft 6 journaled at one end in the carriage 4 and at the other end on any suitable support (not shown). The threaded shaft 6 is engaged by a threaded fixed half-nut 7 so that when the shaft 6 revolves it is also caused to move axially depending upon its direction of rotation.

Rotation of the shaft 6 is caused by rotation of the spindle 1 through the worm 5. Thus the

record tablet 3 is caused to move radially from left to right as it rotates. Secured on the end of the shaft 6 is a ratchet wheel or disc 8 engaged by an electromagnet operated pawl 9 to be referred to later.

The upper surface of the disc 3, which bears the record groove in the form of a spiral beginning near the center of the disc and extending adjacent the periphery thereof, is engaged by the stylus of a sound pick-up or reproducing device 10, illustrated in the drawing as being of the piezoelectric crystal type. In practice this pick-up device will be connected to a loudspeaker or head set through a suitable amplifying system.

The drive wheel 11, mounted on a shaft to be driven from any suitable power source, engages the under surface of the disc 3. Mounted above it is a friction wheel 12 which moves down to engage the upper surface of the disc 3 above the drive wheel 11 when the machine is to be operated so as to press the disc 3 against the rotating drive wheel 11 and thereby cause it to rotate. It is by this rotation of the disc 3 that shaft 6 is rotated through spindle 1 and worm 5, and the whole assembly is caused to translate longitudinally of the shaft 6 as the disc revolves.

The friction wheel 12 is secured on a shaft 13 which is mounted in any suitable form of journal support in such a way that the shaft and wheel can be moved so that the wheel engages or disengages the disc 3. As diagrammatically illustrated, the shaft 13 is mounted in a fixture which is supported by a pair of plungers which are part of the electromagnetic solenoids 14 and 15. When solenoid 15 is energized wheel 12 moves to engage disc 3 and when solenoid 14 is energized it is moved out of engagement therewith.

At 16 is a suitably grounded current source which is connected through main on and off switch 17 by wire 18 to one terminal of each of the magnets 14 and 15. The other terminal of solenoid 14 is connected by wire 19 to a contact 20 and by wire 21 to the movable blade of pause determining switch 22. Contact 20 is positioned so as to be engaged by shaft 13 when wheel 12 engages the disc 3. The other terminal of solenoid 15 is connected by wire 23 to contact 22 and by wire 23 to switch 24 of a relay switch the fixed contact of which is grounded. Contact 22 is positioned as shown to be engaged by shaft 13 when the friction wheel 12 is out of engagement with the disc 3.

An electromagnet 25 controls the operation of the pawl 9 and has one terminal connected to wire 18 and the other connected to ground by wire 26 through the switch 27 of the relay of which the magnet 34 is a part. Wire 26 may also be connected to ground through a switch 30 which may be termed the back-spacing switch. Shaft 13 may be connected to ground through wire 28 and switch 29, which switch is the start-stop switch. Wire 18 is connected by wire 31 through a switch 32 which is the main switch for the entire pause control mechanism. The fixed contact of this switch is connected by wire 33 to one terminal of the magnet 34, one terminal of the magnet 35, and one terminal of the magnet 36. The other terminal of magnet 36 is connected by wire 37 to a grounding switch 38 forming part of the relay 34. The remaining terminal of magnet 34 is connected to the terminal contact at the right hand end of the set of contacts controlled by switch blade 44.

Switches 24, 27 and 38, all part of the relay

34, are open when the magnet of the relay is de-energized. The other terminal of magnet 38 is intermittently connectable to ground through wire 38 and switch 48. Switch 48 is intermittently opened and closed at regular time intervals by means of a timing device 41 which may consist of a power driven cam, as illustrated.

At 42 is a ratchet wheel, mounted on a shaft or pivot pin for rotation thereon. This ratchet wheel is connected by a spring 43 to the fixed shaft or pivot pin. A contact arm 44 is connected to the ratchet wheel mechanically and electrically, for movement therewith. The switch blade 44 is positioned to move over a set of contacts, as shown, which are respectively connected by wires 47 to a corresponding set of contacts forming part of the pause control switch 22. The extreme left hand contact of this switch is connected by a jumper 48 to the extreme right hand contact, as shown. As illustrated, the pivotal support for the ratchet wheel 42 is grounded.

Magnet 36 controls a pawl 45 which normally engages the ratchet wheel 42 and prevents counter-clockwise rotation thereof. A pivoted pawl 46 is operated by electromagnet 35 so that for each energization of this magnet the pawl will move the ratchet wheel 22 one step in a clockwise direction and with it the switch blade 44.

The operation of this system will now be described in detail. The operator places a record disc 3 on the spindle 1, as previously described, raises nut 7 out of engagement with the shaft 6 and shifts it and the carriage 4 to the extreme right. Nut 7 is then engaged with the threaded shaft 6 and reproducer 10 is moved down to engage the innermost convolution of the spiral record groove on the disc 3. The machine is now ready for operation.

Assuming the main power switch 17 is closed, 40 in order to start the machine the transcriber momentarily closes switch 29. This completes a circuit from ground through wire 28, shaft 13, contact 22, wire 23, solenoid 15, wire 18, closed switch 17 and power source 16 to ground. The energization of the solenoid 15 pulls the wheel 12 into engagement with the disc 3. When shaft 13 is operated by either of the magnets 14 and 15, it remains in the position to which it is operated until the other of these magnets is energized, when it is moved to its other position. Assuming that the drive wheel 11 is being rotated from a suitable power source, this will result in the rotation of disc 23 at a constant peripheral speed. As the disc revolves, carriage 4 moves slowly to the left.

The parts are proportioned so that the stylus of the reproducer 10 properly tracks in the spiral record groove and thereby slowly traverses it from the inner end ultimately to its terminal end adjacent the periphery of the disc. As thus described, the recorded sound will be continuously reproduced by the sound reproducing unit connected to the pick-up device 10. If the transcriber is able to transcribe the dictation at this rate of speed, which will be the same rate at which the recording was made, the pause control apparatus need not be used.

At any time the transcriber may back-space the machine to repeat previously reproduced portions of the record by successively closing switch 30 to repeatedly energize the magnet 25 so as to cause pawl 9 acting through the ratchet disc 8 to rotate shaft 6 in the reverse direction. In this reverse movement the carriage 4 is moved back in successive steps but preferably the disc 3

is not caused to revolve in the reverse direction. The stylus of the reproducer simply skips in a radial direction one groove at a time for each closing of the back-spacing switch 30. Thus desired portions of the record may be repeated. 5

If the machine is reproducing at too rapid rate for the transcriber, she moves the switch blade 22 to the right, say for example five steps, so as to leave it in engagement with the centermost contact of the associated group. Switch 32 is closed and the timer 41 is put into operation which may, as is obvious, be also controlled by switch 32 to cause this result. 10

In a preferred embodiment of the machine the cam of the timer will revolve sixty (60) times per minute, it being observed that the average rate of dictation is about 60 words per minute, or one word per second. Each time that switch 40 closes a circuit is completed to the magnet 35 from ground through switch 40, wire 39, magnet 36, wire 33, switch 32, wire 31, switch 17, and current source 16 to ground. For each energization of the magnet 35 the pawl 46 moves ratchet wheel 42 and switch arm 44 one step in a clockwise direction. Thus after five pulses switch blade 44 will engage the centermost contact of its associated group and complete a circuit from ground through switch blade 44, wire 47, interconnecting this contact with that of the other group, switch blade 22, wire 21, wire 19, 15 solenoid 14, wire 18, switch 17, and current source 16 to ground. Thus solenoid 14 will be energized, raising the friction wheel 12 out of engagement with disc 3 which then stops its rotation. With the timing illustrated it will be seen that this 20 will occur after five seconds of dictation. When shaft 13 moves upwardly it engages contact 22. 25

While the transcriber is completing the transcription of the words reproduced during the five seconds above mentioned, switch 40 is continuing to be closed and therefore pawl 46 is continuing the clockwise step by step movement of the switch blade 44. When that switch blade reaches the contact at the extreme right of the associated group, a circuit is completed from ground through switch blade 44, to magnet 34, wire 33, switch 32, wire 31, switch 17, and current source 16 to ground. This causes the energization of the magnet 34 which is of the slow release type, so that switches 24, 27 and 38 are closed and held closed for a suitable length of time. 30

The closing of switch 38 completes a circuit from ground through wire 37 and magnet 36 back to wire 33 so that latch pawl 45 is moved out of engagement with the ratchet wheel 42. As the switch arm 44 moved from the position shown in the drawing to its extreme right hand position, spring 43 was tensioned so that this actuation of pawl 42 releases the ratchet allowing spring 43 to snap switch blade 44 back to its initial position; pawl 46 normally not engaging the ratchet wheel 42 and therefore leaving it free for this reverse movement. 35

The closing of switch 27 has given one impulse to the back-spacing magnet 25 so that at the end of the five seconds of sound reproduction the sound record tablet is back-spaced one groove. The purpose of this is to repeat a short amount of the dictation reproduced during the previous five seconds interval so that the transcriber may connect up the thought of the new five seconds of dictation to follow. At this point it may be noted that with the arrangement shown, it took five seconds after interruption of the reproduction for switch arm 44 to 40

move to the extreme right. Thus the transcriber has five additional seconds to complete the transcription of the matter reproduced during the previous five seconds of reproduction. 45

The closing of switch 24 completes a circuit from ground through wire 23 to solenoid 15, which upon energization moves the friction wheel 12 back into engagement with the disc 3, whereupon it begins to rotate. Sound reproduction, therefore, starts again and after repeating the back-spaced portion causes it to repeat approximately five seconds of fresh dictation, followed by another interruption by the energization of magnet 34 which in the meantime has released switches 24, 27 and 38 so that their circuits are broken. Contacts 20 and 22 are provided, as will be seen, so that when contact 22 is closed the machine which is then at rest may be started up by the starting switch 29 and if the machine is running the closure of switch 29 will complete a circuit through contact 20 to solenoid 14 to energize it and stop the machine. Stopping of the machine as herein referred to means stopping of the rotation of disc 3, the rotation of the drive wheel 11 being controlled in any suitable manner, as by means of the initial closing, for example, of the main power switch 17. 50

If switch blade 22 is in the position shown in the drawing, and switches 17 and 32 are closed and the timer 41 is operating, the switch arm 44 will step across its contacts, as previously described. When it reaches its contact connected to the contact which in turn is connected to wire 48, the machine will stop. On the next impulse given by the timer, switch arm 44 will reach the last contact of its set and again start the machine. This would be the normal operation of the machine for an operator who could keep up in his transcription of the dictation at the full rate of the machine. At this time the pause control mechanism is really of no use, and switch 32 might therefore just as well have been open. In the event, however, that the transcriber under conditions of transcribing at former speed has forgotten to open switch 32, the momentary stopping and starting of the machine will remind him of the fact. 55

From the above description it will be apparent to those skilled in the art that the single embodiment herein set forth for the purpose of disclosing the nature and scope of this invention by no means represents all the various forms which the invention may take. I do not, therefore, desire to be limited to the illustrated embodiment, but rather to the scope of the claims granted me. 60

What is claimed is:

1. In a dictating machine, the combination with a record support, a reproducing device, and means for causing relative movement between said support and device, of means including a preselector for automatically initiating and interrupting said relative movement during one cycle of relative movement between the support and reproducing device at successive intervals whereby the periods of movement and rest may be made equal or unequal. 65

2. In a dictation machine of the type described, the combination including a record support, a reproducing device positioned adjacent said support, means for causing relative movement between said support and reproducing device, means for controlling said means to cause the starting and stopping of said relative movement, and preselector control means for said last 70 75

control means for causing the automatic operation thereof at regular or irregular successive intervals of time.

3. In a dictation machine of the type described, the combination including a record support, a reproducing device, means for causing relative movement between said support and device, means for controlling said last mentioned means to cause the beginning and ending of said relative movement, preselector control means for said last control means for causing the automatic operation thereof at regular or irregular intervals of time, back spacing means for causing reverse relative movement between said support and device, and means controlled by said preselector means for causing operation of said back spacing means at the end of each period of movement of the record support.

4. In a dictation machine of the type described, the combination including a record support, a reproducing device, means for causing relative movement between said support and device, means for controlling said last mentioned means to cause the beginning and ending of said relative movement, preselector control means for said last control means for causing the automatic operation thereof at regular or irregular intervals of time, back spacing means for causing reverse relative movement between said support and device, and means controlled by said preselector means for momentarily energizing said back spacing means simultaneously with the energization of said first control means.

5. In a dictation machine of the type described, the combination including a record support, a reproducing device, driving means for causing relative movement between said support and device, electromagnetic start-stop control means for said driving means, and a preselector device for controlling said start-stop control means in accordance with the preselected conditions whereby the said relative movement may be automatically initiated and stopped at regular intervals.

6. In a dictation machine of the type described, the combination including a record support, a reproducing device, driving means for causing relative movement between said support and device, electromagnetic start-stop control means for said driving means, and a preselector device for controlling said start-stop control means in accordance with the preselected conditions whereby the said relative movement may be auto-

matically initiated and stopped at regular intervals, the intervals of operation and inaction being equal or unequal as previously determined by said preselector means.

7. In a dictation machine of the type described, the combination including a record support, a reproducing device, driving means for causing relative movement between said support and device, electromagnetic start-stop control means for said driving means, and a preselector device for controlling said start-stop control means in accordance with the preselected conditions whereby the said relative movement may be automatically initiated and stopped at regular intervals, said preselector means including a step switch and means for energizing it at regular intervals of time.

8. In a dictation machine of the type described, the combination including a record support, a reproducing device, power drive means for causing relative movement between said support and reproducing device, start-stop control means for initiating and terminating said relative movement, and a preselecting mechanism for energizing said start-stop means to automatically start and stop the record support at regular intervals, including a step switch, electro-magnetic means for operating said switch including a timing device, and means for returning said step switch to an initial position at the end of a preselected period of time.

9. In a dictation machine of the type described, the combination including a record support, a reproducing device, power drive means for causing relative movement between said support and reproducing device, start-stop control means for initiating and terminating said relative movement, and a preselecting mechanism for energizing said start-stop means to automatically start and stop said relative movement at regular intervals including a step switch, electro-magnetic means for operating said switch including a timing device, and means for returning said step switch to initial position at the end of a preselected period of time, and means for causing said relative movement in a reverse direction and means controlled by said step switch for energizing said back spacing means simultaneously with each stopping energization of the start-stop means.

HENRY P. CLAUSEN.
